UNITED STATES PATENT OFFICE

171,030

PAIR OF SPECTACLES

Gerald Courtney, Hollywood, Calif.

Application August 27, 1953, Serial No. 26,608

Term of patent 14 years

(Cl. D57—1)

To all whom it may concern:

Be it known that I, Gerald Courtney, a citizen of the United States of America, residing at Hollywood, in the county of Los Angeles and State of California, have invented a new, original, and ornamental Design for a Pair of Spectacles, of which the following is a specification, reference being had to the accompanying drawing, forming a part thereof.

Fig. 2 is a side elevational view.

Fig. 3 is a plan view.

I claim:

The ornamental design for a pair of spectacles, as shown.

GERALD COURTNEY.
